UNITED STATES PATENT OFFICE

2,458,464

SWITCH

John W. Busacker, Houston, Tex., and Thomas M. Perry, Bennington, Vt., assignors to the United States of America as represented by the Secretary of the Navy

Application January 21, 1943, Serial No. 473,148

2 Claims. (Cl. 200—52)

1

This invention relates to switches and more particularly to a so-called "unshorting" switch of novel construction for normally short-circuiting an electrical device and operable by a force of set-back to remove the short circuit. The new switch is simple and compact in construction and positive in operation.

While the invention is suited for various uses, it may be employed to particular advantage as a safety device in a detonating circuit of a projectile adapted to be fired from a gun. Accordingly, the invention will be described in the form of a switch suitable for use in such a projectile, although it will be understood that the invention may take other forms as well.

One object of the invention resides in the provision of a novel unshorting switch of simple and rugged construction adapted for manufacture at low cost, which is operable by a force of set-back to remove the short-circuit.

Another object of the invention is to provide a switch of the character described in which the short-circuiting element maintains an inertia member in an inoperative position under normal conditions but is broken by the member when the latter is subjected to a relatively heavy force, such as that due to the force of set-back incident to firing a projectile from a gun.

These and other objects of the invention may be better understood by reference to the accompanying drawing, in which

Fig. 1 is a longitudinal sectional view of part of a projectile, showing schematically one use of the switch in the detonating circuit of the projectile;

Fig. 2 is a longitudinal sectional view of one form of the new switch, showing the inertia member in its inoperative position;

Fig. 3 is a view similar to Fig. 2 but showing the inertia member after it has broken the short-circuiting member in response to a force of setback;

Fig. 4 is a plan view of the switch shown in Figs. 2 and 3, and

Fig. 5 is a perspective view of a modified form of the switch.

In the drawing, the unshorting switch 10 is shown mounted in the casing of a projectile 11 containing a detonating squib 12 for exploding the main charge (not shown) in the projectile. The squib is of the electrical type and is adapted to be operated by a fuze 13 connected in series with the squib through wires 14 to form a detonating circuit. Any desired form of fuze may be employed, such as a time-operated fuze or a fuze

2

responsive to proximity of an airplane or other target. The switch 10 is connected between the wires 14 by conductors 15 so that it normally short-circuits the squib 12, the electrical resistances of the switch and the squib being so proportioned that the current normally flowing through the squib is insufficient to operate it.

The switch 10, as shown, comprises a cylindrical body 16 made of insulating material, such as lucite, and having a recess 17 in its rear end portion. An axial bore 18 extends from the recess 17 through the front end of the body. Mounted on the front end of the body are two diametrically opposed terminal plates 19 and 20, formed of brass or other suitable metal, the plates being secured to the body by pins 21. The terminal plates 19 and 20 are provided with terminal screws 22 and 23, respectively, to which the shunt wires 15 may be joined for connecting the switch 20 across the squib 12.

A short-circuiting wire 24 extends between the terminal plates 19 and 20 and is connected thereto in any suitable manner, as by means of solder spots 24a. The wire 24 extends through a passage 25 in the front end portion of a plunger 26 slidably mounted in the bore 18. As shown, the front end of the plunger projects from the bore 18 between the terminal plates 19 and 20, and the rear end of the plunger projects into the recess 17. The weight of the plunger and the tensile strength of the short circuiting wire 24 are so proportioned that the wire is adapted to hold the plunger in its inoperative position (Fig. 2) under normal conditions, as, for example, during handling and loading of the projectile.

In the operation of the new switch, when the projectile 11 is fired from a gun, the force of setback incident to acceleration of the projectile in the gun barrel causes the plunger 26 to move rearwardly in the bore 18 into the recess 17. As a result, the force of the plunger overcomes the tensile strength of the wire 24 and breaks the wire, as shown in Fig. 3, so as to remove the short-circuit of the squib 12 and arm the detonating circuit. The squib is then prepared for operation under control of the fuze 13.

The switch shown in Fig. 5 is similar to that shown in Figs. 2 to 4, inclusive, except that means are provided for supplementing the short-circuiting wire 24 to hold the plunger normally in its inoperative position. More particularly, the plunger 26a is provided on its forward end with a knob 28 partly defining an annular groove 28a to the rear of the knob. A post 29 is mounted on the front end of the switch body 16 adjacent the

plunger and is formed with a circumferential groove for receiving the looped end of a retaining wire 30, which may be made of spring metal. The other end of the wire 30 is looped partly around the plunger 26a in the groove 28a. With this construction, the retaining wire 30 and the short-circuiting wire 24 serve to hold the plunger normally in its inoperative position so that inelastic movement of the plunger is prevented during handling of the projectile and during the usual drop and tumble tests for the fuze. That is to say, the kinetic energy of the plunger will be completely and elastically absorbed by the spring 30 in any drop or jolt test, but said spring will be unable to absorb the accumulated forces of acceleration in the gun bore, with the result that, as the projectile is fired from a gun, the force of set-back causes the plunger 26a to disengage the retaining wire 30 which snaps out of the groove 28a. At the same time, the plunger breaks the short-circuiting wire 24 and moves to the rear into recess 17, whereby the short-circuit is removed.

It will be apparent that the new switch provides a reliable safety means for preventing premature operation of the detonating squib 12. Accidental actuation of the switch by the plunger is effectively prevented by reason of the close fit of the plunger in the bore 18 and because of the inherent tensile strength in the short-circuiting wire 24. The switch includes only a single moving part and may be made in a compact form, and by making the body 16 of cylindrical shape, the switch may be easily fitted in the usual cylindrical chamber in the projectile casing so that it occupies a relatively small space. The wire 24 serves

the dual function of a short-circuiting element and a means for retaining the plunger in its inoperative position.

We claim:

- 5 1. An unshorting switch comprising a short circuiting wire, a retainer adjacent the wire, and a plunger connected to the wire and the retainer and normally held thereby in an inoperative position, the plunger being operable by a force of set-back to break the retainer and the wire.
- 10 2. In combination with a projectile, an unshorting switch including an insulating body having a bore, a pair of terminals on the body, a short-circuiting wire connecting the terminals and extending across the bore, and an inertia member movably mounted in the bore and receiving the short-circuiting wire therethrough, said inertia member being displaced by set-back forces incident to the discharge of the projectile for breaking the wire.
